CHAIN SAW MACHINE

Arthur William Mall, Flossmoor, Ill.

Application April 24, 1942, Serial No. 440,303

1 Claim. (Cl. 143—32)

My invention relates to chain saw machines and has as its primary object the provision of an auxiliary engine for supplying added power to the cutting chain. By employing two engines to drive the cutting chain, I am able to maintain a minimum diameter for the driving sprockets and in turn a minimum width for the chain guide plate.

Another object of my invention is to provide a "floating" chain guide plate.

A further object is to provide improved means for adjusting the guide plate rotatively relative to the engines and for detaching the engines from the guide plate.

A further object of my invention is to provide an improved engine cooling device and engine starting device.

Other objects and advantages of my invention will become apparent upon reading the following specification and upon examination of the drawings in which:

Fig. 1 is a side elevational view of my improved chain sawing machine;

Fig. 2 is a fragmentary sectional view of the adjusting device for adjusting the guide plate rotatively relative to the engines and for detaching the engines from the guide plate;

Fig. 3 is a fragmentary sectional view of one end of the chain saw machine showing the guide plate in a horizontal plane;

Fig. 4 is a fragmentary front view taken on line 4—4 of Fig. 3;

Fig. 5 is a fragmentary sectional view taken on line 5—5 of Fig. 3;

Fig. 6 is a fragmentary sectional view taken on line 6—6 of Fig. 3;

Fig. 7 is a fragmentary detail view of the underneath side of the sprocket supporting casting;

Fig. 8 is a detail front view of the special nut used in connection with the chain tensioning device;

Fig. 9 is an enlarged fragmentary view of the chain tensioning bolt;

Fig. 10 is a fragmentary sectional view of the engine starting device and cooling system;

Fig. 11 is a sectional view of the oil tank condensed from its normal length;

Fig. 12 is an enlarged detail sectional view of the driving sprocket; and

Fig. 13 is a perspective detail view of the crank holding lever.

Referring to Fig. 1 I have shown the preferred embodiment of my invention which is comprised generally of gasoline engines A and B, chain guide plate C and cutting chain D.

The engines A and B may be identical in mechanical construction so as to have interchangeability of parts and they are of the same size and capacity so that each operator carries the same amount of weight when operating the sawing machine. Each engine is provided with a centrifugally operated automatic clutch comprised of a driving clutch member 2 secured to the engine shaft 3 of each engine A and B. The driving clutch member 2 has clutch shoes 4 pivotally mounted on clutch member 2 so as to establish driving connection with driven clutch member 5. Driven clutch member 5 transmits rotation to sprocket shaft 6 through the medium of gear 7 and sprocket 16 drives the cutting chain D. It is to be noted that one engine may be operated without operating the second engine if desired. This is accomplished by virtue of the fact that there is an automatic clutch at each end of the sawing machine. Thus, if engine B were being operated and engine A were idle, the driven clutch member 5 would be rotating (viewing Fig. 3) however, there would be no driving connection between clutch member 5 and clutch shoes 4. The only time clutch shoes 4 establish driving connection with clutch member 5 is when engine shaft 3 is rotated.

Referring to Fig. 1 it will be noted that the chain guide plate C is not shown in its normal position. Fig. 1 shows the cutting edge 12 facing upwardly and the guarded edge 13 facing downwardly. Normally the cutting edge would be directed horizontally as shown in Fig. 3 (such as when cutting down a standing tree) or the cutting edge would be directed downwardly as when cutting a fallen tree into logs. Thus when it is desired to cut a log the cutting edge 12 of cutting chain D is applied to the log and the log rides against curved surface 14 of guide bracket 15.

It is to be noted that when both engines are operating at the same speed, they each impart equal horsepower to the drive sprockets 16 and 17, thereby distributing the torque load equally on each drive sprocket. This distribution of torque load permits the use of a drive sprocket of smaller diameter, thereby, in turn, permitting the use of a chain guide plate D of minimum width. The reason for using a guide plate of minimum width is important when felling a standing tree—the less the width of the guide plate—the sooner a wedge can be driven in the kerf of the tree to prevent the tree from pinching the cutting chain.

It can be seen that when the width of the guide plate is reduced to a minimum, its resistance to

bending is likewise reduced, consequently when my sawing machine is cutting in a horizontal plane, guide plate C is caused to bend arcuately. To remedy this I have provided a pair of straps 19 and 20 having their free ends secured to opposite sides of the engines. The loop portions of the straps may be placed around the operator's neck and shoulders to permit the weight of the sawing machine to be carried by the operator's body as well as his hands and arms which grasp handles 21 and 22. Consequently, it is easy for the operators to exert a slight downward pressure on handles 21 and 22 against the leverage obtained through straps 19 and 20 thereby offsetting or counterbalancing the gravity load on guide plate C and thereby eliminating any tendency of guide plate C to bend.

It can be seen that by using two engines of equal weight and size I have obtained a well balanced sawing machine in which each operator carries an equal amount of weight when operating the sawing machine and at the same time I have supplied twice as much power to the cutting chain D. As previously pointed out, the engines A and B are preferably identical in mechanical construction. Likewise, each end of the sawing machine is provided with lubricating systems of identical construction, engine starting and engine cooling devices of identical construction and transmissions (including automatic clutches, sprockets, and gears) of identical construction.

It is to be noted that gear housings 31 are both located on the same side of guide plate C, whereby when guide plate C is adjusted to a horizontal plane for cutting down a standing tree, then guide plate C can be operated within 2 or 3 inches of the ground, thereby eliminating tree stumps.

Referring to Fig. 3, I have shown the manner in which I provide a "floating" guide plate. Guide plate C is provided with an elongated slot 25 through which bolts 26 extend. Guide bracket 27 is provided with an upwardly extending elongated rectangular shoulder 28 which provides a guide for slot 25 of guide plate C. Guide plate C may be adjusted longitudinally relative to guide brackets 27 and 15 by loosening bolts 26 and manually moving said guide plate. When bolts 26 are retightened, bracket 15 clamps the guide plate C in a fixed position. This effects a rough adjustment of the tension of cutting chain D.

Referring to Figs. 3, 4, 5, 6 and 7, I have also provided a casting 30 which is rigidly secured to gear housing 31. Casting 30 has a downwardly depending annular flange 32 received in the upper end of gear housing 31 and serving as a bearing retainer for bearing 33. Casting 30 also has an outwardly extending shoe 34. Said shoe is provided with a centrally located elongated rectangular shoulder 35, which shoulder is arcuately dished throughout its length at 36 so as to provide a bearing surface for spring 37. Guide bracket 27 is provided with a central bore 38 which receives compression spring 37. Shoulder 35 guides bracket 27 which bracket is formed with an elongated slot 39 so as to be slidable relative to casting 2 and so as to be guided by guide rail 35. It will be noted the bore 38 in bracket 27 has parallel walls 40 and 41 thereby providing a channel having an interior contour corresponding to the exterior contour of nut 42. Nut 42 is, thereby, slidable within bore 38, but is non-rotatable relative thereto. The flat underneath surface of nut 42 rides on shoulder 35. An adjustment screw 44 is threadedly received by nut 42 and has a circu-

lar shoulder 45 which is biased against a semi-circular shoulder 46 on casting 30. The semi-circular shoulder 46 is formed by means of a boss 47 which is integral with casting 30 and which is provided with a slot 49. Screw 44 has a stub shaft portion 50 which is received in slot 49 so as to be rotatable therein. It can be seen that by rotating screw 44, nut 42 is caused to move axially of said screw thereby increasing or decreasing the tension on spring 37 (depending upon the direction of rotation of screw 44). Screw 44 may be rotated by inserting an Allen wrench through hole 48 in bracket 27 into the square hole 51 in the outer end of screw 44. Screw 44 may also be 10 adjusted by using a crescent wrench on head portion 52. It can be seen that when screw 44 is rotated it cannot move axially in the direction of sprocket shaft 6 because of shoulder 45 being biased against shoulder 46. Likewise, screw 44 15 does not move axially in a direction away from sprocket shaft 6 because of the resistance of spring 37 abutting against nut 42. The tension stored in spring 37 is opposed by the tension of cutting chain D which is trained around sprocket 25 8. Therefore it can be seen that the tension of cutting chain D may be accurately adjusted by rotating screw 44 in either direction. It can also be seen that since each end of the sawing machine is provided with the same type of chain 30 tensioning device as shown in Fig. 3, then guide plate C may be considered to "float" between the opposing tensions of springs 37 at each end of the sawing machine.

When cutting chain D is removed from sprocket 16, there is nothing to resist the outward thrust of compression spring 37, consequently, I have provided a pair of parallel slots 56 in the underneath surface of shoe 34. Two pairs of bolts 57 and 58 extend through slots 56 and are threaded 40 into bracket 27 so as to be movable along with bracket 27. Said bolts have shoulders 59 which prevent threading them too far into bracket 27. A pair of flat bars 60 and 61 provide a flat bearing surface for riding against the underneath surface of shoe 34. When bolts 57 and 58 are tightened 45 so as to cause shoulders 59 to be tightened against the underneath surface of bracket 27, then there is enough "play" to permit sliding movement of bracket 27 relative to shoe 34 within the limits 50 of slots 56. Thus when cutting chain D is removed from sprocket 16, spring 37 urges bracket 27, guide bracket 15 and guide plate C outwardly until bolts 57 and 58 reach the ends of slots 56.

I have provided an automatic lubrication system for lubricating the cutting chain at all times while the sawing machine is operating. Mounted on each end of the sawing machine is an oil container 64 secured to gear housings 31 by means of strap irons 65. Each oil tank 64 has a plunger 66 therein which is continually under tension by compression spring 67. When refilling the oil tank, plunger 66 is retracted by pulling handle 68 outwardly. The oil is then inserted through opening 69 and a sealing cap 70 (not shown in Fig. 11) is threaded into opening 69. A second opening 71 in the oil tank has a conduit 72 (Fig. 3) threaded thereinto which conduit is also threaded into gear housing 31 thereby directing the oil from tank 64 into compartment 73 in gear housing 31. It can be seen that the oil from tank 64 is urged into compartment 73 under pressure at all times due to spring 67 acting on plunger 66. The oil travels through oil passage 74 in sprocket shaft 6 until it reaches passage 75 (Fig. 12) also 70 75 in the sprocket shaft. Passage 75 opens into pas-

sages 76 in sprocket hub 77. The oil then travels through passages 78 which open into the sprocket teeth 79. The sprocket teeth construction may be of the type shown in the co-pending application, Serial No. 436,014, by myself and Walter L. Gorden. In order to assure that the cutting chain will be lubricated automatically while the saw is operating, which lubricant supply is cut off when the saw is not operating, I have provided a centrifugally operated valve device which will admit lubricant to the sprocket teeth regardless of what position the sawing machine may be in.

The valve device is comprised of a plurality of balls 81 preferably spaced 90 degrees from each other so as to have a total of four. Each ball is radially movable within cylindrical chamber 82. The bottom of each chamber 82 is dished to form a valve seat 83 having a contour corresponding to the spherical contour of balls 81 so that when the balls 81 are seated in said valve seats 83, the oil in passage 76 is prevented from flowing past balls 81. In Fig. 12 I have shown one of the balls 81 in its normal seated position and the other ball in unseated position.

When the engine is not running sprocket shaft 6 is idle and compression springs 85 urge balls 81 into seated position. Set screws 86 may be adjusted to vary the tension of springs 85. When the engines are started up, sprocket shaft 6 is rotated, thereby imparting rotation to sprocket hub 77. When a predetermined speed of rotation of sprocket hub 77 is reached, centrifugal force causes balls 81 to overcome the resistance of springs 85 and said balls move radially outwardly so as to permit the oil in passage 76 to flow through passage 78 into the sprocket teeth. The teeth of cutting chain D are consequently lubricated as they travel around sprocket teeth 79. In order to prevent sawdust from clogging passages 78, I have provided enlarged tapered openings 89 in the sprocket teeth 79 which facilitate disposal of sawdust.

Referring to Figs. 1 and 2, I have provided means for rotatively adjusting guide plate C and cutting chain D relative to engines A and B so as to permit sawing in either a horizontal or a vertical plane without changing the position of the engines A and B from their normal upright positions as shown in Fig. 1. Said rotative adjustment means also permits separating the two engines from the guide plate and cutting chain, whereby to facilitate transporting the sawing machine from one locality to another. Gear housing 31 has a circular flange portion 92 which embraces a circular flange portion 93 of engine casting 94. Flange 92 may be provided with a series of four or more openings 95 into which steel bushings 96 may be cast. Flange 93 is also provided with an equal number of openings 97 to register with the openings in steel bushings 96. It is to be noted that the inner periphery of flange 92 and the outer periphery of flange 93 are tapered for reasons which will be hereinafter described. Formed integrally with engine casting 94 are two bosses 98, one located on each side of engine casting 94 so as to be diametrically opposite each other. Said bosses have an interior surface 99 which is arcuately concaved (not shown in drawings) so as to conform to the arc defined by the exterior periphery of flange 92. It is to be noted that the outer annular edge 100 of flange 93 abuts against annular shoulder 101 formed at the base of flange 92. A second annular shoulder 102 is also formed in flange 92. A pin 103 extends through boss 98 into

the openings in steel bushings 96 and openings 97 in flange 93. Said pin 103 is normally anchored in the position shown in Fig. 2 by means of a spring pressed ball 104 seated in annular groove 105 in pin 103.

When it is desired to rotate guide plate C, cutting chain D and gear housing 31 relative to engine casting 94, pins 103 are manually retracted to the positions shown in dotted lines in Fig. 2. Then gear housing 31 is manually rotated to the desired position of adjustment and pins 103 are pushed back into the openings in flanges 92 and 93 to anchor gear housing 31 relative to engine casting 94. The tapered exterior periphery of flange 93 and the tapered interior periphery of flange 92 facilitate rotative movement of gear housing 31 relative to engine casting 94.

It is to be noted that when gear housing 31 is rotated to a new position of adjustment, peripheral edge 100 of flange 93 rides against annular shoulder 101 thereby serving to keep the openings 96 and 97 aligned in a common radial plane so as to facilitate inserting pin 103 into said openings.

When it is desired to detach gear housing 31 from engine casting 94, this is accomplished by loosening screw 106 which is threaded into the outer end of boss 98. Bar 107 is then manually pulled outwardly within the limits of slot 108 and the inner end of bar 107 which protrudes beyond the inner face of boss 98 adjacent annular shoulder 102 is retracted so as to permit shoulder 102 to pass by bar 107 as gear housing 31 is pulled in an axial direction away from engine casting 94. Bar 107 is bent at its outer end so as to provide a stop 105 for preventing pin 103 from being completely removed from boss 98.

Referring to Figs. 1 and 10 I have shown my improved engine starting and engine cooling devices. Starter housing 110 is secured to a second engine casting 111 by means of bolts 112. Housing 110 has an eccentrically located sleeve portion 113 extending into the interior of said housing. The inner end of said sleeve 113 is reduced in diametric dimension so as to provide a bearing for the inner end of starter sleeve 114. Sleeve 114 is provided with internal teeth 115 which mesh with the external teeth on starter pinion 116. A bushing 117 is threaded into sleeve 113 so as to provide a bearing for the outer end of sleeve 114 and also to provide a stop shoulder 118 to limit the outward movement of sleeve 114 relative to sleeve 113. A spring washer 119 is anchored in an annular groove in sleeve 114 and normally abuts against stop shoulder 118 as a result of compression spring 126 which is always under tension. A channel iron is secured to the outer end of sleeve 114 by welding and a handle 121 is secured to the outer end of channel iron 120 forming a hand crank generally referred to as 121A. An elongated slot 122 is located in the outer end of channel iron 120 for receiving the outer end of arm 123. Arm 123 is pivotally mounted within bifurcated boss 124 on housing 110 and a torsion spring 125 normally urges arm 123 about its pivot in a counter-clockwise direction (viewing Fig. 10) so as to rest against the wall of housing 110.

When starting the engine, crank 121A is manually pushed inwardly until teeth 115 engage pinion 116 secured to engine shaft 116A. As soon as the engine starts, spring 126 urges the crank 121A outwardly into the position shown in Fig. 10. In order to maintain the gear teeth 115 out of engagement with pinion 116, arm 123 is swung

outwardly (clockwise viewing Fig. 10) and the hook 127 is inserted into slot 122. The width of slot 122 is only slightly more than the width of hook 127, consequently the stop shoulders 128 (Fig. 3) on either side of hook 127 engage the outer face of channel iron 120 thereby preventing crank 121A from moving axially inwardly and in turn preventing teeth 115 from engaging with pinion 116.

Embracing sleeve 113 is a multi-bladed fan 130, the blades 131 of which extend radially outwardly from hub 132 to the outer supporting ring 133. Said blades are angularly inclined relative to the axis of hub 132 as indicated by an edge of said blades being shown in section at 134. Consequently, the air flows from fan 130 in an axial direction as indicated by the arrows in Fig. 10. A second fan 136 is multi-bladed and its blades 137 extend radially outwardly from engine shaft 116A and also extend axially relative to engine shaft 116A. Consequently fan blades 137 direct the air centrifugally outwardly as shown by the arrows in Fig. 10. Both fans 130 and 136 are secured together through the medium of an annular ring member 138. The fans are spaced from each other so that fan 130 supercharges fan 136 thereby increasing the amount of air discharged by fan 136 around the cylinder walls of the engine, and in turn affording a cooler running temperature for the engines. It is to be 30

understood that my invention contemplates the use of electric motors or air motors as well as gasoline engines for supplying the motive power and I do not wish to be limited to gasoline engines.

Having thus described my invention what I claim is:

A chain saw machine comprising a power unit, a chain guiding member extending therefrom, a transmission housing, a sprocket rotatably supported by the transmission housing, a cutting chain trained about the sprocket and chain guiding member, a bracket member secured to the transmission housing, an opening in the bracket 15 through which the sprocket shaft extends, a trough in the bracket member, a carrier having its underneath surface spanning the trough and riding on the upper surface of the bracket, a spring resting in the trough and in a groove in 20 the carrier, an adjustment screw extending into the interior of the spring, a shoulder at one end of the bracket against which one end of the screw abuts, a nut threaded onto the screw and having a flat underneath surface spanning the trough, said spring abutting the nut and urging one end of the adjustment screw against the bracket shoulder and an opening in the end of the carrier whereby the adjustment screw may be adjusted.

ARTHUR WILLIAM MALL.
